MASSACHUSETTS.

SHUTTLE.

1,065,592.

Specification of Letters Patent. Patented June 24, 1913.

Application filed May 11, 1910. Serial No. 560,578.

To all whom it may concern:

Be it known that we, JEAN B. DAUDELIN and EUSEBE H. DAUDELIN, citizens of the United States, residing at Fall River, county 5 of Bristol, Commonwealth of Massachusetts, have invented certain new and useful Improvements in Shuttles, of which the following is a specification.

This invention relates to shuttles and particularly to that type of shuttle known as the hand threader in which the thread is drawn through a tortuous passage into its ultimate line of delivery. As is well illustrated by the art, there has been a constant 10 effort to secure a shuttle of this type which would be completely satisfactory. While shuttles have been produced which would give at least fairly satisfactory results in operation they have for the most part been 15 only producible at a cost which rendered their substitution slow and their use expensive.

It is the object of the present invention to produce a hand threading shuttle 25 which will not only be positive in its threading and safe against the escape of the thread, but, shall be strong and capable of production at a low price. This we have accomplished through the substitution of a 30 guiding and trapping structure for the bushing, with which most of our former patents have dealt. The construction of these parts and their operation will be more fully described in the specification which follows:

In the drawings we have shown as an 35 illustrative embodiment an arrangement which we find well adapted to practical use and also a modification which illustrates still further the application of the principles involved.

Throughout specification and drawings like reference numerals are employed to indicate corresponding parts, and in the drawings:—Figure 1 is a plan view of one end 45 of the shuttle equipped with our invention, Fig. 2 is a side elevation of the same, Fig. 3 is a plan view of our plate structure removed from the shuttle, Fig. 4 is a section on the line 4—4, Fig. 1, Fig. 5 is a side view 50 of our plates removed, Fig. 6 is a plan view of the end of the shuttle equipped with a modified form of the device shown in Fig.

1, and Fig. 7 is a side elevation of the modified form shown in Fig. 6.

1 is a shuttle having the usual bobbin 55 chamber 1¹ in which a bobbin 2 is mounted on a spindle 3.

4 is a transverse plate longitudinally disposed in a delivery passage. The plate 4 has centrally of its forward edge a notch 5 60 from which an incline runs up to a point 7 which may be upturned, as shown, to secure a slight bearing in the shuttle body, if desired. The plate 4 is slotted near one end, as indicated at 15. 65

9 is a second plate longitudinally disposed in the shuttle but at right angles to the plate 4. The plate 9 has a notch 11 at one end. This notch is preferably formed in a general triangular shape with rounded corners 70 and a restricted outlet. At one side of the plate 9 it is curved up toward the outlet to give a gradually rounded edge along which the thread may run in entering the recess 11, while on the opposite side of the outlet 75 is a projection 14 which acts as a stop to throw the thread into the recess 11. On the opposite edge of the plate is a projection 10 which fits within a corresponding recess in the rear edge of the plate 4 so as to lock 80 the two plates together. Thus, when the plates are inserted, as shown in Fig. 4, the plate 9 may be held by the screw 12 and thus at the same time the plate 4 will be locked in place. The open mouth of the plate 9 extends through the plate 4 so that the recess 85 11 opens on the opposite side of the plate 4.

In the form of the device shown in Figs. 1 to 5, inclusive, a threading slot 6 is cut forward so as to enter the forward part of 90 the transverse delivery recess 8 and in this position it passes around the forward end 7 of the plate 4. In this form of the device the thread in passing through the slot 6 would at once pass over the forward end 7 95 of the plate and on account of the incline from the notch 5 to the point 7 the thread would be worked back to the notch 5 which is its proper position in delivery. Meanwhile, in traveling back along the incline 100 toward the notch 5 the outer end of the thread 2 is brought back under the plate 7 until it strikes the rounded forward end of the plate 9 up which it travels until its de-

lection through the slot 15 and finally striking the stop 14 is forced down into the delivery notch 11. When in this position the thread is guided between the notch 5 and the notch 11.

In the modified form, shown in Figs. 6 and 7, the guiding slot 6¹ enters the transverse delivery recess 8¹ to the rear of the point 7¹ of the plate 4. The plate 4 in this instance is positioned centrally of the passage 8¹ but has its point 7¹ upturned and projecting within a recess or hollowed out portion in the upper wall of the passage 8¹ so as to be covered. In passing this point 15 the thread is deflected around the point passing through the recess which with the point acts as a guard against its return.

When the thread is drawn down through the slot 6¹ it first strikes the upper side of the plate 4 and is drawn along by a forward movement until it is deflected by the tip 7¹. After passing this point it may be drawn back by a rearward motion, as described in connection with the form first set forth. 25 During this rearward passage the thread runs back to the notch 5 and the outer end of the same ultimately is located in the notch 11. In both instances it is to be noted that the slot 6 or 6¹ emerges just behind a shoulder 6² at the end of the bobbin chamber. The mouths of the threading passage 6 and 6¹ are, therefore, covered so that in addition to the other locking of the thread the entry of the thread through the slot by ballooning 35 is prevented.

Various modifications may be made in the operation and structure of our device, all without departing from the spirit of our invention if within the limits of the ap- 40 pended claims.

What we, therefore, claim and desire to secure by Letters Patent is:—

1. In a shuttle of the class described having a bobbin chamber, a transverse delivery opening, and a threading slot leading into said delivery opening, a slotted plate longitudinally disposed in said opening, a second plate in said opening and located longitudinally thereof but at right angles to said first named plate, said second plate having a re-

cessed end extending through the slot in the first named plate, whereby the mouth of said recess opens on the opposite side of the first named plate.

2. In a shuttle of the class described having a bobbin chamber, a transverse delivery opening, and a threading slot leading into said delivery opening, a plate longitudinally disposed in said opening and having a forward notch disposed centrally of the shuttle 55 and a longitudinal slot near one side of the shuttle, a second plate at one side of said opening and located longitudinally thereof but at right angles to said first named plate, said second plate having a narrow mouthed 60 recess in its end, said end extending through the slot in the first named plate, whereby the mouth of said recess opens on the opposite side of the first named plate.

3. In a shuttle of the class described, a 70 plate having a notch centrally disposed on one of the edges and a slot near one end, and a second plate having a notched end, the notched end of said plate loosely entering the slot of said plate to form a thread 75 trap.

4. In a shuttle of the class described having a transverse delivery opening, a longitudinal tongue having a slot therein and an upturned tip at its forward end, said tip 80 being covered by a recess in the shuttle body but leaving a passage on each side of said tongue and a thread trap consisting of a plate having a forked end projecting through the slot of said tongue. 85

5. In a shuttle of the class described having a transverse delivery opening therein, a longitudinal tongue having a slot, said tongue located in said opening and having a thread passage on each side of it and a 90 forked thread trap consisting of a plate having its open end projecting through the slot in said tongue.

In testimony whereof, we affix our signatures in presence of two witnesses.

JEAN BAPTISTE DAUDELIN.
